UNITED STATES PATENT OFFICE.

JOSEPH ALBERT RONCHETTI, OF WOONSOCKET, RHODE ISLAND, ASSIGNOR, BY MESNE ASSIGNMENTS, TO THE NOISELESS TYPEWRITER COMPANY, OF MIDDLETOWN, CONNECTICUT, A CORPORATION OF CONNECTICUT.

TYPE-WRITING MACHINE.

1,094,816.

Specification of Letters Patent. Patented Apr. 28, 1914.

Application filed June 5, 1908. Serial No. 436,749.

To all whom it may concern:

Be it known that I, JOSEPH A. RONCHETTI, a subject of the King of Italy, residing at Woonsocket, in the county of Providence and State of Rhode Island, have invented certain new and useful Improvements in Type-Writing Machines, of which the following is a full, clear, and exact description, such as will enable others skilled in the art 10 to which it appertains to make and use the same.

This invention relates to typewriting machines, and one of the objects thereof is to provide new and improved means for connecting the space bar with the spacing mechanism.

Another object of the invention is to provide means whereby the spacing mechanism may be actuated at the instant of the commencement of the downward or upward strokes of the key levers or space bar.

Another object is to provide new and improved means for arresting the movements of various operative parts of a typewriting machine in a silent manner.

Other objects will be in part obvious and in part pointed out hereinafter.

The invention accordingly consists in the features of construction, combinations of elements and arrangement of parts which will be exemplified in the construction herein-after set forth, and the scope of the application of which will be indicated in the following claims.

In the accompanying drawings, wherein is illustrated one of the various possible embodiments of my invention, Figure 1 is a plan view illustrating the various features thereof; Fig. 2 is a side elevation thereof, partly in section, taken substantially on line 2—2, Fig. 1; Fig. 3 is a view similar to Fig. 2, the parts being shown in a different position; Fig. 4 is a rear view, showing the means for arresting the universal bar, the view being taken substantially on line 4—4, Fig. 2, and the parts being shown in normal position; Fig. 5 is a view similar to Fig. 4, but taken on the line 5—5, Fig. 2, showing the position of the parts when the universal bar is depressed by one of the key levers; Fig. 6 is a sectional view, on an enlarged scale, taken on line 6—6, Fig. 4.

Similar reference characters refer to simi-

lar parts throughout the several figures of the drawings.

Referring now to the drawings, 1 denotes a portion of the framing of the machine and 2 the escapement shaft carrying the escapement wheel 3 and the feed-pinion 4 which meshes with the carriage rack, a portion of 60 which is shown at 5. 6 represents a rocker member upon which is mounted a fixed dog 7 and a movable dog 8 which coöperate with the escapement wheel 3 to afford a feed of the carriage. This rocker member is mounted upon pivot screws 10 carried by brackets 11 erected upon the frame of the machine and is provided with a forwardly extending arm 12 to which it is attached as by means of a pivot-screw 13 and an actuating link 14, 70 said link being in turn connected, as by means of a pivot-pin 15, to an arm 16 mounted loosely upon the universal rock shaft 17. Rock shaft 17 extends transversely of the machine and is supported at its ends by 75 trunnion screws 18 extending through the side walls of the framing of the machine. Stops for limiting the oscillatory movements of rocker member 6 are provided at 20 and 21, respectively, said stops being constituted 80 by pointed screws adjustably mounted in an extension 22 of one of brackets 11. Arm 12 of rocker member 6 engages these screws when oscillated, and the extent of oscillation thereof is determined by such engagement. 85 Arm 16, which is mounted upon the universal rock shaft, is provided with a cone-shaped portion 23 which is received in a conical-shaped recess 24 formed in a collar 25 fixed upon said rock shaft, as by means 90 of a pin 26. The cone-shaped portion 23 is maintained in engagement with the walls of recess 24 by means of an extensible spring 27 positioned upon shaft 17 and interposed between said arm and a collar 28 fixed upon the 95 rock shaft and held in any desired adjusted position thereon, as by means of a set-screw 30. The construction just described establishes a frictional connection between the universal rock shaft and the rocker member 100 6, so that, at the instant of the commencement of the oscillation of the rock shaft 17 in either direction, rocker member 6 will be oscillated until arm 12 thereof is engaged with either of stops 20 or 21, whereupon 105 during a further rocking movement of said

rock shaft the frictional engaging surfaces of the collar 25 and arm 16 will slip on each other until the universal shaft completes its full stroke. It will accordingly be seen that the rocker member which carries the feed dogs will be oscillated at the instant of commencement of rotation of the universal rock shaft in either direction.

The key levers, one of which is shown at 31, rest upon the universal bar 32 which, as shown, is suspended upon links 33 carried by arms 34 mounted upon the universal rock shaft 17, cushioning means, as at 35, being interposed between the universal bar and the key levers.

Mounted upon a stud-screw 36 threaded into a bracket 37 suitably attached to the framing of the machine is an oscillatory cam member 40. This cam member, which is shown in normal position in Fig. 4, has a cam path 41, the upper end of which is disposed substantially vertical, said vertical portion merging into a concave portion 42, the surface of which is formed upon an arc of decreasing radius and ending in a portion 43 which is disposed substantially concentric to the axis of oscillation of the cam member. 44 indicates a roller which is journaled upon a pivot pin 45 supported in ears 46 depending from the side portions 47 and 48 of the universal bar. This roller, in the present instance, is located centrally of the universal bar directly above the central axis of the stud-screw 36 upon which the cam 40 is mounted, the cam path 41 of said cam member being held in engagement with said roller by means of a retractile spring 50 attached to a rearward extension 51 of the cam member and interposed between said extension and a bracket 52 fixed in the framing of the machine. It will be seen that during the downward movement of the universal bar, as when a key lever is depressed, roller 44 will cause an oscillation of the cam member 40 from the position shown in Fig. 4 of the drawings to that shown in Fig. 5, the roller meanwhile traversing the curved portion 42 of the cam path until it reaches the portion 43 thereof which is disposed concentrically with the axis of oscillation of the cam member, whereupon the movement of the universal bar will be arrested. It will also be seen that a constantly increasing resistance is interposed to the downward movement of the universal bar and that the same will be arrested without any impact or concussion whatever.

In order to eliminate any tendency of the universal bar to movement in an endwise direction during depression caused by the engagement of roller 44 with the oscillatory cam member, a fixed bracket 53 is provided, said bracket having a vertically disposed face 54 upon which runs a pair of rollers 55 and 56 mounted upon pivot pin 45. The

engagement of these rollers with this bracket causes the universal bar to travel downwardly in a vertical line. The universal bar is restored to normal position after depression by means of a spring 57 which is extended between a pin 58 fixed to the side wall of the machine and a rearwardly extending portion 60 of one of the arms 34 from which the universal bar is suspended.

61 denotes the space bar which is supported upon the forward ends of space levers 62 and 63 which are mounted upon a rock shaft 64 journaled upon trunnion-screws 65 threaded through brackets 66 formed upon the framework of the machine, and extended between space levers 62 and 63 is a rod 67. Upon this rod is mounted a link 68, said link being pivotally attached, as at 70, with a link 71, the upper end of the latter link being pivotally attached, as at 72, to an arm 73 fixed upon the universal rock shaft. Links 68 and 71 furnish an actuating connection between the space levers and the universal rock shaft, so that, when the space bar is depressed, the universal rock shaft will be oscillated to actuate the spacing mechanism; and it will be noted that, when the space bar is depressed, the universal bar, through its connection with the universal rock shaft, will also be depressed, whereupon the oscillatory cam member 40, will, through the above described mechanism, operate to arrest the downward movement of the space bar without impact or concussion. The space bar is restored to its normal position after depression by means of spring members 74 and 75, fixed as at 76 to the framework of the machine, said springs engaging with collars 77 fixed upon rod 67, said collars also operating to maintain link 68 against endwise movement upon said rod. Link 68 is provided with a projecting ear 78 against which a flat spring 80 engages said spring exerting a tension tending to swing link 68 in the direction indicated by the arrow, so that when the universal bar is depressed by a key lever, links 68 and 71 will be flexed at their points of pivotal connection, as shown in Fig. 3 of the drawings; thus allowing the space bar to remain stationary when the universal bar is depressed by the key levers.

Having thus described the construction of the present embodiment of my invention, the operation thereof, which should be obvious, is substantially as follows: As has been explained above, when one of the key levers is depressed to effect printing, the universal bar 32 is correspondingly depressed, thereby, through its connection with the universal rock shaft, oscillating the latter and actuating the space mechanism, said latter mechanism being frictionally connected to the universal bar so as to be

actuated at the instant of the commencement of the downward stroke of a key lever. During the downward motion of the universal bar, roller 44 travels along the cam path 41 of the oscillatory member 40 and its downward motion is gradually arrested by means of the curved face 42 and is ultimately arrested when roller 44 engages the portion 43 of said cam path. During this downward motion, rollers 55 and 56 traveling upon the vertical face of bracket 53 cause the universal bar to travel downwardly in a vertical line. When the space bar is depressed, the spacing mechanism is similarly actuated through the connection of the universal rock shaft 17 with said space bar, and the universal bar is at the same time moved downward without, however, affecting any of the key levers. As will be understood, the links 68 and 71 flex or bend at their point of pivotal connection whenever the universal bar is depressed by a key lever.

It will accordingly be seen that I have provided mechanism well adapted to attain, among others, all the ends and objects above pointed out, in a simple, yet efficient, manner. The frictional connection interposed between the universal rock shaft and spacing mechanism provides for an actuation of the spacing mechanism at the instant of the commencement of the movement of the universal rock shaft in either direction, and thus quickens the feed of the carriage without in any wise obstructing a full stroke of the universal bar or the key or space levers.

Another advantage inherent in the present construction is that the collapsible link connection interposed between the space levers and the universal rock shaft permits either the space bar or the key levers to be actuated without causing a corresponding movement of the other.

Still another advantage inherent herein is that the movements of all the operative parts are noiselessly arrested by means of the cam member interposed beneath the universal bar.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent is:

1. In a typewriting machine, the combination with the spacing mechanism, a universal rock shaft and the universal bar connected therewith, of the character keys which actuate the universal bar when de-

pressed, a space bar, and an independent flexible connection interposed between the space bar and the universal rock shaft.

2. In a typewriting machine, the combination with the spacing mechanism, a universal rock shaft connected therewith and a universal bar connected with the universal rock shaft, of the character keys which rest upon the universal bar and actuate the same when depressed, a space bar, and collapsible means for connecting the space bar with the universal rock shaft, whereby either the character keys or the space bar may be actuated without causing an actuation of the other.

3. In a typewriting machine, the combination with the spacing mechanism, a universal rock shaft connected therewith and adapted to actuate the same, and the universal bar suitably connected with said universal rock shaft and adapted to actuate the latter, of the key levers which rest upon the universal bar, a space bar, flexible connecting means interposed between the space bar and the universal rock shaft, and means for flexing said connecting means when the universal bar is depressed by one of the key levers, whereby the space bar may remain stationary during the depression of said key levers.

4. In a typewriting machine, the combination with the spacing mechanism, a rock shaft connected therewith and the universal bar connected with said rock shaft, of the key levers which rest upon the universal bar, a space bar, a system of linkage interposed between the space bar and said rock shaft, and means for flexing said system of linkage when the universal bar is depressed by the key levers, whereby the space bar may remain stationary.

5. In a typewriting machine, the combination with the spacing mechanism, of a rock shaft connected therewith, a universal bar connected with said rock shaft, the key levers resting upon the universal bar and actuating the same when depressed, a space bar, a pair of pivotally connected links interposed between the space bar and said rock shaft, and means for automatically flexing said links at their point of pivotal connection when the universal bar is depressed by one of the key levers.

6. In a typewriting machine, the combination with the spacing mechanism, of a universal rock shaft connected therewith, a universal bar connected with said rock shaft, a plurality of key levers resting upon the universal bar, space levers carrying the space bar, a pair of pivotally connected links interposed between the space levers and said rock shaft, and means for flexing said links at their point of pivotal connection when said universal bar is depressed by the key levers, said space levers being adapted to

compel a downward movement of the universal bar when they are depressed through a connection thereof with said rock shaft.

7. In a typewriting machine, the combination with the spacing mechanism, of a rock shaft connected therewith and adapted when rocked to actuate the same, a universal bar suspended from said rock shaft and adapted to actuate the latter, a plurality of key levers resting upon the universal bar, a space bar, space levers supporting said space bar, a flexible connection interposed between the space levers and said rock shaft, means for flexing said connection when the universal bar is depressed by the depression of a key lever, whereby the space bar may remain stationary, said space bar when depressed being adapted to compel a depression of the universal bar when the former is depressed through its flexible connection with said rock shaft, and means coöperating with said universal bar to arrest the downward movements of the key levers and space levers.

25 8. In a typewriting machine, the combination with the spacing mechanism, of a rock shaft connected therewith adapted when rocked to actuate the same, a space lever, a pair of pivotally connected links interposed between the space lever and said rock shaft, a plurality of key levers, a universal bar upon which the key levers rest, means for flexing said links at their point of pivotal connection when the universal bar is depressed by a key lever, whereby the universal bar may be depressed independently of a movement of the space lever when actuated by the key levers, but is impelled to movement by the depression of the space lever, and means acting through said universal bar to arrest the downward movements of either the key levers or the space lever.

45 9. In a typewriting machine, the combination with the spacing mechanism, of a universal rock shaft connected therewith, a universal bar connected with said rock shaft, a plurality of key levers resting upon the universal bar and adapted to actuate the same when depressed, a pair of spaced levers, a space bar carried by said levers, a rod interposed between said levers, a pair of pivotally connected links interposed between said rod and said rock shaft, whereby the latter part is actuated during a depression of the space bar, and means for flexing said links at their point of pivotal connection when said rock shaft is actuated through its connection with the universal bar, whereby the space levers may remain stationary.

60 10. In a typewriting machine, the combination with the spacing mechanism, a universal rock shaft connected therewith, and a universal bar connected with said rock shaft, of a plurality of key levers resting upon said

universal bar and adapted to be actuated thereby, a space lever, a space bar mounted thereon, a pair of pivotally connected links interposed between the space lever and said rock shaft, whereby the latter will be actuated when the space bar is depressed, and means for moving said links at their point of pivotal connection when the universal bar is depressed by the key levers, whereby the space lever may remain stationary.

70 11. In a typewriting machine, the combination with the spacing mechanism, of a universal rock shaft connected therewith, a universal bar suspended from said rock shaft, key levers resting upon the universal bar, a space lever, a system of collapsible-linkage interposed between the space bar and said rock shaft, and means for collapsing said linkage when the universal bar is depressed by the key levers.

75 12. In a typewriting machine, the combination with the spacing mechanism, of a rock shaft connected therewith, a universal bar suspended from the rock shaft, a plurality of key levers resting upon the universal bar, a pair of space levers carrying the space bar, a rod interposed between said space levers, a link journaled upon said rod, a link pivotally connected with said first-mentioned link, an arm extended from said rock shaft and connected with said second-mentioned link, and spring means for flexing said links at their point of pivotal connection when the universal bar is depressed by the key levers.

80 13. In a typewriting machine, the combination with the spacing mechanism, of a rock shaft connected therewith, a universal bar suspended from the rock shaft, a plurality of key levers resting upon the universal bar, a space bar, and a jointed link interposed between the space bar and said rock shaft which forms an actuating connection between those parts.

85 14. In a typewriting machine, the combination with the spacing mechanism, of a rock shaft connected therewith, a universal bar suspended from said rock shaft, a plurality of key levers resting upon the universal bar, a pair of space levers carrying the space bar, a rod interposed between said space levers, a jointed link interposed between said rod and said rock shaft which forms an actuating connection between the latter and said space levers, and a spring 115 for automatically flexing said link at its point of jointure when the universal bar is depressed by a key lever.

90 15. In a typewriting machine, the combination with the spacing mechanism, of a rock shaft connected therewith, a universal bar suspended upon arms extending from said rock shaft, a plurality of key levers resting upon said universal bar, a pair of space levers; a space bar mounted upon said 120

space levers, a rod connecting said space levers, a jointed link; one end of which is connected with said rod and the other end of which is connected with said rock shaft, 5 whereby an actuating connection is established between the space bar and said rock shaft, a spring engaging said jointed link and adapted to flex the same at its point of jointure when the universal bar is depressed 10 by a key lever, whereby the space bar may remain stationary, and spring means engaging said rod and adapted to return the space levers to normal position after depression.

16. The combination with a movable part 15 of a typewriting machine, of means for arresting the movements thereof comprising a roller carried by the movable part, a member mounted to oscillate upon a fixed portion of the machine having a concavely formed 20 cam path a portion of which is located in a curve having its center at the axis of oscillation of said member, said roller being adapted to run along said cam path during part 25 of the movement of the movable part and swing the same until the portion thereof which is concentric with the axis of oscillation is engaged by said roller, and spring means connected with said cam member and adapted to hold the same in constant engagement 30 with said roller.

17. The combination with a movable part 35 of a typewriting machine, of means for arresting the movements thereof without impact or concussion, comprising a fixed part, a roller carried by one of said parts, a member mounted to oscillate upon the other of said parts, said members having a concavely formed cam path, a portion of said path being disposed in a curve having its center at 40 the axis of oscillation of said member, said roller during a movement of the movable part being adapted to run along said cam path until engaged with the portion of the same which is concentric with its axis of oscillation whereupon the movement of said 45 movable part will be arrested, and spring means connected with said cam member and operating to hold the cam surface thereof in constant engagement with said roller.

50 18. In a typewriting machine, the combination with the universal bar and the key levers which rest upon said universal bar, of means for arresting the downward movements of the key levers without impact or 55 concussion, comprising a roller journaled upon the universal bar, a cam member mounted to oscillate upon a fixed portion of the framing of the machine and having a concavely formed cam path, the surface of 60 which is formed upon an arc of decreasing radius, said cam path having a portion thereof which is concentric with the axis of oscillation of said cam member, said roller during a depression of said universal bar being adapted to traverse the cam path of said

cam member until brought into engagement with the portion of the latter which is disposed concentrically to the axis of oscillation of said cam member, and a spring connected with said cam member and adapted to oppose an oscillation thereof during a depression of the universal bar. 70

19. In a typewriting machine, the combination with the universal bar and the key levers which rest thereon, of means for arresting the downward movements of the key levers without impact or concussion, comprising a roller mounted upon the universal bar, a member having a concavely formed cam path along which said roller runs when the universal bar is depressed, and means for maintaining the cam portion of said member and said roller in engagement. 75

20. In a typewriting machine, the combination with the universal bar and the key levers which rest thereon, of means for arresting the movements of the key levers when depressed, comprising a roller mounted upon said universal bar, a cam member adapted to oscillate upon a fixed portion of the machine, said cam member having a concavely formed cam path, the latter having a portion thereof disposed concentrically with the axis of oscillation of said cam member, and a spring connected with said cam member and adapted to hold the cam path of the latter in engagement with said roller, said roller being adapted to run along said cam path until the portion thereof which is concentric with the axis of oscillation of said cam member is reached, whereby the movement of said roller and associated parts will be arrested. 90

21. In a typewriting machine, the combination with the universal bar and the key levers which rest thereon, of means for arresting the downward movement of the universal bar when impelled by a key lever, comprising a roller mounted upon the universal bar, a member mounted to oscillate upon a fixed portion of the machine, said member having a concavely formed cam path, a portion of the cam path of said member being disposed substantially parallel with the plane of movement of the periphery of said roller, said cam path thereafter merging into a curve having a gradually diminishing radius and having a portion thereof at the end of said curved portion disposed concentrically with the axis of oscillation of said member, and a spring connected with said cam member and holding the cam surface thereof in engagement with said roller. 110

22. In a typewriting machine, the combination with the universal bar and the key levers which rest thereon, of means for arresting the downward movement of the universal bar, comprising a roller carried by the universal bar and a member mounted to oscillate upon a fixed portion of the ma 120

130

chine, having a concavely formed cam path adapted to be traversed by the roller during a descent of the universal bar, and spring means for holding the cam path of said member and said roller in engagement.

23. In a typewriting machine, the combination with the universal bar and the key levers which rest thereon, and means for arresting the downward strokes of the universal bar without impact or concussion, comprising a roller mounted upon the universal bar, an oscillatory cam member mounted upon a fixed pivot, said cam member being provided with a concave cam path, spring means for maintaining said cam path in engagement with said roller, and means for guiding the universal bar and holding the same against endwise movement when the same is depressed.

24. In a typewriting machine, the combination with the universal bar and the key levers which rest thereon, of means for arresting the downward stroke of the universal bar without impact or concussion, comprising a roller mounted upon said universal bar, a member provided with a concave cam path mounted to oscillate upon a fixed pivot, a spring connected with said member and holding the cam path thereof in engagement with said roller, a guide roller mounted upon the universal bar, and a fixed bracket with which said guide roller engages, whereby said universal bar is maintained against endwise movement when the same is depressed.

25. In a typewriting machine, the combination with the universal bar, the key levers which rest thereon, and means for arresting the downward strokes of the key levers without impact or concussion, comprising a roller mounted upon the universal bar, a concavely formed cam mounted to oscillate upon a fixed pivot of the frame of the machine, a spring for maintaining said cam in engagement with said roller, and means for preventing an endwise movement of the universal bar during its downward or upward movements.

26. In a typewriting machine, the combination with the universal bar and the key levers which rest thereon, of means for arresting the downward movement of the universal bar without impact or concussion, comprising a roller mounted upon the universal bar, a concavely formed cam member mounted to oscillate upon the fixed pivot, a spring connected with said cam member and holding the same in engagement with said roller, and means for guiding the universal bar when the same is depressed by one of the key levers.

27. In a typewriting machine, the combination with the spacing mechanism, of a universal rock shaft for actuating the spacing mechanism, an actuating connection in-

terposed between said rock shaft and the spacing mechanism, and means for frictionally connecting said actuating connection with said rock shaft.

28. In a typewriting machine, the combination with the spacing mechanism, comprising a rocker member carrying the fixed and movable feed-dogs, a universal rock shaft and an actuating connection interposed between said rocker member and said rock shaft, and frictionally connected with the latter.

29. In a typewriting machine, the combination with the universal bar and the key levers which rest thereon, of means for arresting the movements of the key levers when depressed, comprising a roller mounted upon the universal bar, an oscillatory cam member mounted upon a fixed portion of the machine, and means for preventing an endwise movement of the universal bar when the same is depressed by one of the key levers.

30. In a typewriting machine, the combination with the universal bar and the key levers which rest thereon, of means for arresting the downward strokes of the universal bar without impact or concussion, comprising a roller mounted upon the universal bar, an oscillatory cam member mounted upon a fixed pivot, spring means for maintaining said cam member in engagement with said roller, and means for guiding said universal bar and for preventing the same from moving endwise when depressed.

31. In a typewriting machine, the combination with the universal bar, of a plurality of key levers resting thereon, a roller mounted upon the universal bar, an oscillatory cam member disposed beneath said roller, a fixed pivot for said cam member, spring means for holding said cam member in engagement with said roller, a plurality of guide rollers mounted upon the universal bar, and a fixed guide member along which said last mentioned rollers run when the universal bar is depressed, whereby the latter is held against endwise movement during depression.

32. In a typewriting machine, the combination with the spacing mechanism, comprising a rocker member carrying the fixed and movable feed-dogs, a universal rock shaft, an actuating connection interposed between said rocker member and said universal rock shaft, and means located upon said rock shaft which frictionally engages said actuating connection.

33. In a typewriting machine, the combination with the spacing mechanism, comprising a rocker member carrying the fixed and movable feed-dogs, means for limiting the oscillatory movements of said rocker member, a universal rock shaft, connecting

- means interposed between said rock shaft and said rocker member, and means for frictionally engaging said connecting means with said rock shaft.
34. In a typewriting machine, the combination with the spacing mechanism, comprising a rocker member carrying the fixed and movable feed-dogs, a pair of oppositely disposed stops which limit the oscillatory movements of said rocker member, a universal rock shaft, and an actuating connection attached to said rocker member and having a frictional engagement with said rock shaft.
35. In a typewriting machine, the combination with the spacing mechanism, comprising a rocker member carrying the fixed and movable feed-dogs, opposed stops for limiting the oscillatory movements of said rocker member in either direction, a universal rock shaft adapted to be actuated by the key levers or space bar, an arm mounted upon said rock shaft and frictionally connected with the latter, and a link connecting said arm and said rocker member.
36. In a typewriting machine, the combination with the spacing mechanism, comprising a rocker member carrying the fixed and movable feed-dogs, opposed adjustable stops for determining the extent of the oscillatory movements of said rocker member, a universal rock shaft adapted to be actuated by the key levers or space bar, an arm loosely mounted upon said rock shaft and having a friction portion, a collar fixed upon said rock shaft and having a friction portion, spring means for maintaining said friction portions in engagement, and a link interposed between said arm and said rocker member.
37. In a typewriting machine, the combination with the spacing mechanism, comprising a rocker member carrying the fixed and movable feed-dogs, a pair of opposed adjustable stops for limiting the oscillatory movements of said rocker member, a universal rock shaft adapted to be independently actuated by the universal bar or the space bar, an arm loosely mounted upon said rock shaft and having a conical-shaped friction portion, a collar fixed upon said rock shaft and having a correspondingly shaped friction portion with which the friction portion of said arm engages, and a
- spring for maintaining said friction portions in engagement, means for adjusting the tension of said spring, and a link interposed between said rocker member and said arm.
38. In a typewriting machine, in combination with a reciprocating member, an oscillating member mounted on a relatively fixed part of the machine, a roller carried by one of said members, a cam path formed on the other of said members adapted to contact with said roller silently to stop the movement of said reciprocating member, resilient means for holding roller and cam path in engagement and means to guide the reciprocating member to prevent a lateral movement.
39. In a typewriting machine, in combination, a rock shaft, a rocker member mounted thereon, an actuating member, and a pair of frictional devices on said shaft, one of which is loose and connected with said actuating member and the other of which is fast on the shaft, whereby motion of the actuating member is immediately transmitted thereby in either direction to said rocker member.
40. In a typewriting machine, in combination, a rock shaft, a rocker member mounted thereon, an actuating member, a pair of frictional devices on said shaft, and spring means on said shaft for urging said frictional devices into engagement, one of said frictional devices being loose and connected with said actuating member and the other frictional device being fast on the shaft, whereby motion of the actuating member in either direction is transmitted to said rocker member.
41. In a typewriting machine, in combination, a rock shaft, a rocker member mounted thereon, and frictional devices between the rocker member and said rock shaft, said rocker member being entirely dependent for its movement in either direction from the power transmitted through said frictional devices.

In testimony whereof I affix my signature, in the presence of two witnesses.

JOSEPH ALBERT RONCHETTI.
